UNITED STATES PATENT OFFICE.

ERNST H. HUENEFELD, OF CINCINNATI, OHIO.

DESIGN FOR A HEATING-STOVE.

SPECIFICATION forming part of Design No. 31,014, dated June 13, 1899.

Application filed May 15, 1899. Serial No. 716,959. Term of patent 14 years.

To all whom it may concern:

Be it known that I, ERNST H. HUENEFELD, of Cincinnati, in the county of Hamilton and State of Ohio, have invented a new and original Design for Heating-Stoves, of which the following is a full, clear, and exact description, reference being had to the accompanying drawings, forming a part thereof.

In the accompanying drawings, Figure 1 is a perspective view taken from the side, and Fig. 2 is a plan view.

The leading feature of my design consists of a heating-stove body oval in horizontal cross-section and mounted on legs, the upper portion of the latter overlapping the lower portion of the body, and a cylindrical body exterior to the oval body and joining said oval body near the base and resting throughout its length in close proximity to said oval body.

A is the oval stove-body, provided near its

upper and lower ends with corrugations or beads b and on its front with the upwardly-projecting cylindrical body B. This cylindrical body B is joined at its base to the oval body, near the base of the latter, and rests 25 throughout its length in close proximity to said oval body, as clearly shown in Fig. 1. The oval body is mounted on legs C, the upper ends of which latter overlap the lower edge of said oval body, and the latter is surrounded by a cylindrical ring c and the conceal part d.

What I claim is—

The design for a heating-stove as herein shown and described.

ERNST H. HUENEFELD.

In presence of—

JOHN R. CARTER,
JACOB P. BAUER, Jr.
